DESIGN FOR A FOLDABLE MINIATURE CARDBOARD SHRINE

Alfred Ochs, New York, N. Y.

Application April 25, 1944, Serial No. 113,373

Term of patent 3½ years

(Cl. D29—23)

To all whom it may concern:

Be it known that I, Alfred Ochs, without nationality, residing at 230 Fifth Avenue, New York, in the county of New York and State of New York, have invented a new, original, and ornamental Design for a Foldable Miniature Cardboard Shrine, of which the following is a specification, reference being had to the accompanying drawing, forming part thereof.

Fig. 1 is a front view in the set up state of the foldable miniature shrine embodying my new design and

Fig. 2 is a horizontal sectional view taken on line 2—2 of Fig. 1.

Fig. 3 is a vertical sectional view taken on line 3—3 of Fig. 1.

I claim:

The ornamental design for a foldable miniature cardboard shrine, as shown.

ALFRED OCHS.
